UNITED STATES PATENT OFFICE.

WILLIAM H. EDWARDS, OF GRAND RAPIDS, MICHIGAN, ASSIGNOR TO THE PROUDFIT LOOSE LEAF COMPANY, OF GRAND RAPIDS, MICHIGAN, A CORPORATION OF MICHIGAN.

LOOSE-LEAF BINDER.

1,291,449.

Specification of Letters Patent.

Patented Jan. 14, 1919.

Application filed March 30, 1917. Serial No. 158,510.

To all whom it may concern:

Be it known that I, WILLIAM H. EDWARDS, a citizen of the United States, residing at Grand Rapids, in the county of Kent and 5 State of Michigan, have invented new and useful Improvements in Loose-Leaf Binders, of which the following is a specification.

The present invention relates to loose-leaf binders, and its object is to provide an improved wear plate between the cover of the binder and the leaves therein contained; and further, to provide such a wear plate comprising a folded strip readily attachable to a base, as the fly-leaf of the binder.

15 This object is attained by, and the invention finds preferable embodiment in, the structure hereinafter described and illustrated by the accompanying drawings, in which:—

20 Figure 1 is a fragmentary side view of a loose-leaf binder;

Fig. 2 is a sectional view of the same taken on a plane corresponding to line A—B of Fig. 1;

25 Fig. 3 is a view in perspective of a portion of the fly-leaf or base and the folded strips attached thereto; and

Fig. 4 is a view in perspective of one of said strips partially folded.

30 In the embodiment of the invention chosen for illustration by the drawings and for detailed description in the body of this specification, the loose-leaf binder shown has a pair of covers 1, 2, connected by flexible and

35 preferably resilient leaf-holding members extending between them, as the spring steel bands 3, 4, which pass through suitable slots (not shown) in the binding edges of the removable leaves 5 in the well-known manner,

40 and extend under clips 6 on the inside of covers to points of secure attachment, as the lugs 7 on the covers which engage holes 8 in the bands.

The bands may be adjustable longitudinally and relatively to the binding edges 9 of the covers by suitable means, as by inserting the lugs into one or another of the holes disposed in the bands' longitudinal direction. These clips 6 are positioned in-

50 wardly from the binding edges of the covers thus connecting the bands to the covers at a short distance from said binding edges. As the covers are swung to open or close the binder, their binding edges have a turning movement on the parts between the cov-

ers, which tends to wear such parts and to mar the leaves if these binding edges engage the same. To obviate this, I provide an improved wear plate 10 comprising a base 11 which may be that portion of the fly-leaf 12 which is adjacent to its binding edge. The wear-plate comprises also a strip 13, as of suitable bendable metal, folded or bent longitudinally around the outside edge of said base and embracing its opposite sides. A 65 portion of the outer fold 14 of this strip is inclined outwardly at 15 toward the binding edge of the device, on which inclined portion the binding edge of the cover engages in its turning movement. Toward the 70 inside edge of the outer fold, such fold has a portion 16 which contacts with the base, and another portion 17 which thus contacts with the base adjacent its outside edge. One of the folds has a flange 18 which turns over 75 the inside edge 19 of the base. The strips are secured to the base by suitable means, as by the spurs 20 formed integral with the other fold of the strip and which are pressed into the base. The strip is formed with par- 80 tially closed folds as shown in Fig. 4, and is passed over the outside edge of the base, whereupon the folds are pressed together, the flange 18 extending over and contacting with the inside edge of the base and the spurs 85 being pressed into it.

The strips are made in sections of suitable length to be attached in alined relation, and with spaces between them, to allow the passage of the leaf-holding members through 90 suitable slots 21 in the bases and between the ends of the strips, as shown in Fig. 3.

As stated, the bases are preferably portions of the fly leaves themselves and are connected to the body of such fly leaves by 95 flexible and thinner portions 22.

It will be seen that as the covers are closed their binding edges 9 ride up on the inclined portions 15 of the strips and thus the cov- 100 ers tend to remain closed owing to the fact that the leaf-holding members depart from the inner sides of the covers at a distance from their binding edges. These inclined portions also raise the covers so that more room for adjusting means on the cover and 105 near its binding edge is provided: and furthermore, inasmuch as the strip is firmly secured to the base, which has considerable width, the strip is prevented from tilting on a longitudinal axis, and the binding edges 110

of the covers are in their turning movement restricted to the hollow provided by the angular disposition of the portions 15 and 16. These inclined portions also prevent the binding edges of the covers from passing beyond the outside edge of the strips when the covers are closed.

What is claimed is:

1. In a device of the character described having a pair of covers and a leaf-holding flexible member extending between the covers and connected to their inner sides at a short distance from their binding edges; a wear plate adapted to be engaged by the binding edge of a cover in its turning movements, and comprising a base having an opening through which passes the leaf-holding member, and a strip folded longitudinally around the outside edge of the base and embracing its sides and securely attached to the base and extending inwardly between the base and the binding edge of the cover.

2. In a device of the character described having a pair of covers and a leaf-holding flexible member extending between the covers and connected to their inner sides at a short distance from their binding edges; a wear plate adapted to be engaged by the binding edge of a cover in its turning movements, and comprising a base having an opening through which passes the leaf-holding member, and a strip folded longitudinally around the outside edge of the base and embracing its sides and having integral spurs thrust into the base for securing said strip thereto.

3. In a device of the character described having a pair of covers and a leaf-holding flexible member extending between the covers and connected to their inner sides at a short distance from their binding edges; a wear plate adapted to be engaged by the binding edge of a cover in its turning movements, and comprising a base having an opening through which passes the leaf-holding member, and a strip folded longitudinally around the outside edge of the base and embracing its sides and extending inwardly between the base and the binding edge of the cover, and having a portion of its outer fold inclined outwardly toward the binding edge of the device; and means for securely attaching the strip to the base.

4. In a device of the character described having a pair of covers and a leaf-holding flexible member extending between the covers and connected to their inner sides at a short distance from their binding edges; a wear plate adapted to be engaged by the binding edge of a cover in its turning movements, and comprising a base having an opening through which passes the leaf-holding member, and a strip folded longitudinally around the outside edge of the base

and embracing its sides, and having a portion of its outer fold contacting with the outer side of the base toward its inside edge, another portion inclined outwardly toward the binding edge of the device, and another portion contacting with the outer side of the base adjacent its outside edge; and means for securely attaching the strip to the base.

5. In a device of the character described having a pair of covers and a leaf-holding flexible member extending between the covers and connected to their inner sides at a short distance from their binding edges; a wear plate adapted to be engaged by the binding edge of a cover in its turning movements, and comprising a base having an opening through which passes the leaf-holding member, and a strip folded longitudinally around the outside edge of the base and embracing its sides, and having the edge of one fold turned over the inside edge of the base, and means for securely attaching the strip to the base.

6. In a device of the character described having a pair of covers and a leaf-holding flexible member extending between the covers and connected to their inner sides at a short distance from their binding edges; a wear plate adapted to be engaged by the binding edge of a cover in its turning movements, and comprising a base having an opening through which passes the leaf-holding member, and a strip folded longitudinally around the outside edge of the base and embracing its sides, and having the edge of one fold turned over the inside edge of the base, the edge of the other fold having integral spurs pressed into the base.

7. In a device of the character described having a pair of covers and a leaf-holding flexible member extending between the covers and connected to their inner sides at a short distance from their binding edges; a wear plate adapted to be engaged by the binding edge of a cover in its turning movements, and comprising a base having an opening through which passes the leaf-holding member, and a strip folded longitudinally around the outside edge of the base and embracing its sides, and having a portion of its outer fold contacting with the outer side of the base toward its inside edge, another portion inclined outwardly toward the binding edge of the device, and another portion contacting with the outer side of the base adjacent its outside edge, the edge of one fold of the strip being turned over the inside edge of the base, and the edge of the other fold having integral spurs pressed into the base.

8. In a device of the character described having a pair of covers and a leaf-holding flexible member extending between the covers and connected to their inner sides at a short distance from their binding edges; a

wear plate adapted to be engaged by the binding edge of a cover in its turning movements, and comprising a base having an opening through which passes the leaf-holding member, and a bendable strip folded longitudinally around the outside of the base and having a portion of its outer fold inclined outwardly toward the binding edge of the device, the edge of one fold of the strip having an inwardly turned flange and the edge of the other fold having inwardly turned integral spurs, the folds being adapted to be bent toward each other to embrace the inside edge of the base by the flange and to press the spurs into the base and 15 the folds into contact with the sides of the base.

In testimony whereof I have hereunto set my hand.

WILLIAM H. EDWARDS.
